ington, N. J., a corporation of New Jersey

Original application April 6, 1946, Serial No.
660,233. Divided and this application Decem-
ber 6, 1947, Serial No. 790,111

1 Claim. (Cl. 12—142)

1

The present invention relates to the sewing of heavy leather and like materials and, among other uses, has great utility in the machine manufacture of shoes. In its illustrated form the invention is hereinafter set forth in connection with a machine particularly claimed in an application for United States Letters Patent Serial No. 660,233, filed April 6, 1946, in the name of the present inventor, of which application the present application is a division.

In the practice of the invention advantage is taken of certain heretofore unappreciated qualities of recently developed types of threads made of synthesized plastic fibers, such qualities including extraordinary extensibility and a peculiar property of delayed recovery characterized by a substantial amount of residual contractility which persists for a considerable length of time after any stretching force which has been exerted upon the thread is reduced.

Because of these characteristics, which differ greatly from those of cotton or linen thread, these new threads cannot be used satisfactorily in, for example, the conventional inseam and outsole sewing machines as employed in commercial shoe manufacture with cotton or linen thread, but it has been discovered that, by establishing a new relation between certain of the thread handling parts of such machines and changing their action in certain respects, the synthetic fiber thread not only can be used successfully but seams can be made having new and unexpected characteristics which render the sewed article definitely superior to similar articles as heretofore made.

The invention consists in the novel features hereinafter fully disclosed and described in their various aspects in connection with the accompanying drawings, in which

Fig. 1 is a sectional view, illustrating the principal parts of a shoe sewing machine adapted for use in carrying out the present invention, together with a portion of a shoe upon which the method of the invention is being performed, the parts of the machine being indicated in positions taken after the needle has been retracted during the formation of a stitch;

Fig. 2 is a detail plan view of a portion of a shoe being presented to the machine, with the machine parts in the positions of Fig. 1;

Fig. 3 is a view similar to Fig. 1, with portions of the frame omitted and with parts in positions assumed directly after a stitch is set;

Fig. 4 is a detail plan view of a portion of a shoe presented to the machine with the parts in the positions shown in Fig. 3;

2

Fig. 5 is a sectional view of a portion of a shoe, illustrating the relations between the parts immediately after a seam has been inserted;

Fig. 6 is a similar view of a portion of a sewn shoe, illustrating the condition of the seam after an extended period of time has elapsed;

Fig. 7 is a detail diagrammatic view of a tension wheel, illustrating the action when relatively inextensible sewing thread is employed in the machine of Fig. 1;

Fig. 8 is a time chart, illustrating the improved manner of operation of the machine, with a comparison between the action occurring when linen thread under normal operating conditions is employed and when a specially prepared thread, such as nylon, is employed;

Fig. 9 is a characteristic stress-strain diagram, comparing linen, cotton and nylon threads; and

Fig. 10 is a sectional view taken along the line X—X of Fig. 1, showing a portion of the tension brake actuating mechanism.

The method of the present invention is illustrated as employed in the manufacture of a Goodyear welt shoe in which a sole member is permanently attached to an upper by an inseam the stitches of which are under heavy tension approaching the breaking strength of the thread employed, to bring the parts into close conformity with a last on which they are mounted. The inseam sewing operation thus supplements the lasting operation in stretching the upper over the last and in giving it its final tension to bring it into close-fitting relationship with the surfaces of the last. Because of the heavy tension required in the thread to bring the parts together, a heavy thread is customarily employed, having a diameter sometimes approximating one-sixteenth of an inch in its largest sizes, commonly designated as "12—" or "14-cord" thread. In some instances, for lighter weight shoe manufacture, smaller sizes of thread are employed but, in any case, a tension is exerted which is heavy for thread of the size being used.

Referring to Figs. 5 and 6 of the drawings, a Goodyear welt inseam is illustrated by a section taken through a shoe. The shoe is ready for inseam sewing after the upper, indicated at 2, has been applied to a last 4, given a preliminary tension, and connected to the upstanding rib on an insole 6 by means of a series of staples, one of which is indicated at 8, passing through the rib and the marginal portion of the upper 2. The rib of the insole projects substantially at right angles to the general plane of the insole and is set back a short distance from the edge of the insole, providing a feather on the insole which

forms an angle of slightly more than 90° with the rib. After the lasting and stapling operations, the upper ordinarily is held under such tension that it bridges the angle between the rib and the feather on the insole.

During the inseaming operation, a grooved welt strip 10 is directed against the outer surface of the upper and a chain-stitch inseam 12 is formed with the stitches entering the groove of the welt and passing through the upper, the exposed threads appearing on the welt and in the angular channel between the insole rib and the upper surface of the insole inside the rib. It is the practice to insert the inseam as close to the upper surface of the insole as is practicable so that the stitches act to draw the bridged upper securely into the angle between the rib and the feather of the insole.

With extremely heavy work, such as that found in military footwear, it is difficult if not impossible to bring the upper, bridged from the staples in the rib to the feather on the insole, closely into conformity with the angle between the two parts of the insole. This difficulty is increased by the resistance of the welt to bending along the line of the groove therein, such resistance adding to the tension in the thread necessary to break the materials down into the angle of the insole. When the materials are insufficiently broken down, there is a void space, indicated at 14, between the upper and the angle of the insole. In many instances, the thread is ruptured before conformity is obtained or, where the substance of the rib, upper or welt is weak, the thread will cut through the parts before closing the void space.

The next operations on the shoe are the inseam trimming, during which the upper portion of the sewing rib, including the staples 8, is cut off close to the inseam, and the welt beating operation for flattening the remaining portions of the rib, upper and welt more closely together against the bottom of the last. The welt beating operation assists in some degree in filling up the void space 14 but, at best, it is only an expedient. After the shoe is completed by attachment of an outsole to the welt 10 and the last is removed from the shoe, the forces exerted upon the inseam during wear of the shoe will cause the inseam, when linen or cotton thread is used, to open up between the welt and upper, exposing the inseam thread to entry of moisture and other destructive agents and constituting a weakness in the construction of the shoe which reduces its effective life, besides giving it an unattractive appearance.

Even under the best conditions, with extreme tension in the thread, the shoe parts are compressed somewhat by the thread but, because of a peculiar characteristic of delayed compressibility found in all leather, full compression is not obtained in the parts until an appreciable length of time has elapsed after each stitch is inserted. Thus, even though a tension be applied to the thread of an intensity close to its breaking strength in setting each stitch, the tension thereafter becomes gradually reduced as the leather yields comparatively slowly to the pressure of the thread. In some instances, with inextensible thread, after the work yields, the tension may be reduced to a small fraction of that employed to set the stitch within a few minutes after the seam has been sewn. If the thread itself does not have sufficient contractility to take up the compression of the parts operated upon, there

will be no possibility of closing up void spaces, such as that indicated at 14.

Cotton and linen threads now in general use, and having elongation and contraction of only 5 from three to ten per cent, do not follow up the compression of heavy leather or similar stiff substances, of a thickness substantially greater than the diameter of the thread, sufficiently to hold the materials together securely and tightly.

In the shoe constructed by the method of the present invention, even if the seam after being inserted has insufficient tension to draw the parts together without void spaces such as indicated at 14, the thread employed is so composed and 10 treated, as will be explained, that it will have sufficient elasticity or contractility to close up such spaces while the shoe is retained on the last and will maintain the parts securely in contact after the void spaces are closed up, with a firm 15 seating throughout the area of contact. The tightening action due to contraction of the thread takes place within a few hours of the time the seam is inserted and is of an extent greater than 20 the yielding action of the substances held under compression by the thread. With a proper balance of forces, the upper will be brought into conformity with the shape of the last and the parts 25 will be maintained securely and firmly together, without danger of separation under the stress 30 of wear, for a time far in excess of that required to wear out the leather in the shoe, with the result that no opportunity is provided for entry 35 of deteriorating agents into vital points of the shoe structure.

Examples of materials which can be utilized 40 successfully as sewing threads in the manner outlined above are synthetic, fiber-forming materials such as nylon (polyamide resin of protein-like structure), rayon (cellulose base materials),

45 vinylidene or Vinyon (polymerized vinyl compound), or the like, given the proper mechanical working and heat treatment after either formation of the basic fiber or of the completely spun thread.

To assist in orientation of the molecules and to 50 reduce as much as possible the tendency of sewing threads to stretch while in use, substantially all such fiber-forming materials from which they are composed are ordinarily at some time during 55 their manufacture subjected to heat and mechanical stretching treatment, frequently accompanied by the application of chemicals. Stretching treatment also strengthens the threads composed of such fibers until eventually they display 60 characteristics of strength and durability in the maximum possible degree.

According to this invention, instead of carrying out the stretching treatment in such 65 threads to an ultimate maximum as usual, the stretching is terminated substantially before that maximum is reached and a thread is produced having sufficient strength for shoe inseam sewing and other similar operations while at the same time retaining a marked degree of elastic 70 and other qualities which assist in later contraction. Such thread has a character which may be termed high contractility and which enables the fibers to become elongated somewhere within the range of from twenty to fifty per cent before 75 breakage. Thus, if such a thread is employed for shoe inseam sewing operations, sufficient strength is retained in the thread to retain the shoe parts in assembled relation, while at the same time the ability to contract after a stitch setting tension has been released is sufficient to close up any

void spaces left between the parts during the sewing operation, as well as to offset the compressibility of the parts after the seam has been inserted.

In order to insert an inseam connecting the welt, upper and insole of a Goodyear welt shoe, using specially treated highly contractile thread of the type employed in the shoe construction herein described, it has been found unnecessary to exert such heavy tensions during sewing as are used in the formation of the usual inseam in which commercial linen or cotton threads are employed. It is only essential to apply to such specially treated thread while each stitch is being set sufficient initial tension to stretch the thread to such a degree that its subsequent contraction will draw the parts securely and firmly together while the shoe is on the last and the delayed compression of the parts will be wholly offset, so as to prevent substantial release of tension in the thread after the seam is formed and the last is removed from the shoe. Thus, it becomes possible to reduce the initial stitch setting tension in the thread substantially below the intensity which will draw the shoe parts securely and firmly together immediately at the time the stitch is set. Furthermore, after setting each stitch, the initial tension is retained in the stitch without permitting slippage of the thread through the substance of the shoe parts or such release as will cause substantial loosening of that stitch after being set or while the succeeding stitch is being formed.

With a reduced initial stitch setting tension, also, the tension may more readily be controlled uniformly from one stitch to another than with higher initial tensions, the only requirement being a retention of sufficient residual contractility in the thread to draw and maintain the parts into firm contact with each other after the seam is inserted. Moreover, it is no longer necessary to apply a lubricant or hot wax to the thread to insure uniform tightening action of the stitches during sewing operations.

For performing the method of the invention illustrated herein a machine has been provided of a type similar in some respects to that of the inseam shoe sewing machine disclosed in United States Letters Patent No. 1,030,743, granted June 25, 1912, upon application of William C. Meyer, and No. 1,108,560, granted August 25, 1914, upon an application of Andrew Eppler. The stitch forming devices comprise a curved hook needle 16, a looper 18, a thread finger 20, a main take-up 22, an auxiliary take-up 24, and a frictionally retarded rotary thread tension wheel 26. The needle 16 oscillates about a stud 28 toward and from the work, entering the groove in the welt, passing through the portion of the upper which is bridged across between the sewing rib and the feather on the insole, and finally penetrating the base of the sewing rib to receive the thread within its hook from the looper. The thread finger thereafter acts to hold aside a portion of thread, as indicated in Fig. 3, between the last-formed stitch and the looper before the needle is looped. The main take-up 22 is actuated by a cam 33 on a main sewing shaft 32 of the machine at the proper time to give up thread during the retracting stroke of the needle (Figs. 1 and 2) and to take up thread as the needle enters the work until a final stitch setting tension is applied by upward movement of the take-up just before the thread is engaged by the thread finger. The auxiliary take-up is pressed downwardly continuous-

ly by a plunger 34 between the upper end of which and an adjustable threaded plug 36 there is disposed an auxiliary take-up compression spring 38.

The tension wheel 26 is secured to a shaft 40 rotatable in the machine frame and having keyed thereto a brake drum 42 acted upon by a brake shoe 44. The brake shoe is pivotally mounted on a lever 46 fulcrumed at 48 on the machine frame and acted upon along its straight upper surface by a pair of adjustable abutments 50 and 52.

The abutments 50 and 52 are slidably mounted on a pair of individually spring-pressed actuating levers 54 and 56, respectively. To adjust the tension on the thread, the abutments have threaded openings to receive adjusting screws 58 provided with suitable knurled heads rotatable in the levers. The actuating levers 54 and 56 for the brake shoe 44 are pivotally mounted at their rearward ends on a stud 60 in the frame of the machine and, at their forward ends, the levers are forced downwardly by a vertical tension rod 62 slidably mounted in a perforated fixed lug 64 at its lower end and arranged to bear against a short arm 66 serving as a balancing member to distribute the downward pressure at the lower end of the rod 62 equally against the actuating levers 54 and 56. The upper end of the tension rod carries a tension wheel brake spring 68 compressed between an adjustable collar 70 clamped to the rod 62 and a perforated arm of a governor-actuated lever 72, through the perforation of which the upper end of the rod 62 passes loosely.

The manner of operation of the conventional machine of this type using a substantially inextensible thread composed of either linen or cotton will now be described. Referring to Fig. 8 of the drawings, it is apparent that the take-up stroke of the take-up occurs between 70° and 125° of rotation of the main sewing shaft while the needle engages the work, or during less than one sixth of the time in each complete sewing cycle. Assuming that the machine is operating at a speed of 600 cycles per minute or 10 cycles per second, the take-up stroke of the take-up occurs within one sixtieth of a second. The major portion of the active stroke of the take-up is utilized in taking up the slack in the thread so that only a small portion (approximately 25° main shaft rotation) of the take-up stroke, indicated at 73, actually can cause thread to be pulled past the tension wheel, the brake 44 resisting rotation of the tension wheel at other times. It can be assumed, therefore, that the velocity of inextensible linen thread as it is being pulled past the tension wheel ranges upwardly to an amount of 120 inches per second maximum. At this velocity, the tension wheel is rotated so rapidly that there is provided a substantial surplus of thread between the tension wheel and the work as a result of overthrow caused by failure of the brake 42 to bring the tension wheel to rest the exact instant at which the tension on the thread is released. On account of variations in mechanical adjustments and conditions of the work, the surplus in the amount of thread drawn past the tension wheel during each stitch varies substantially from one sewing cycle to another. To reduce this variation of surplus thread in the machine of the Eppler patent, the pressure on the tension wheel brake is increased in each sewing cycle in a manner set forth in United States Letters Patent No. 2,424,991, granted on August 5, 1947, upon an application of Henry A. Landroche by actuating the spring-pressed lever 56 to bring the abutment

52 into engagement with the brake supporting lever 46. During the take-up stroke of the take-up, the tension on the thread thus is increased, as indicated by the line labeled "Friction increase" in Fig. 8, and the auxiliary take-up is moved against the stop screw 74. As soon as a stitch is set and the take-up completes its stroke, the friction is again decreased to enable easy withdrawal of thread if necessary for the succeeding stitch formation. Decrease in friction is obtained by raising the abutment 52 from the lever 46 to a position indicated in Figs. 1 and 10. During the time the friction is decreased, the needle is looped and is retracted to the position of Fig. 1, with the loop of thread carried in its hook. At this time, the take-up is giving up thread to the needle so as to provide little or no tension in the thread which will resist the retracting movement of the needle. If any substantial degree of tension exists at this time, the auxiliary take-up 24 yields a short length of thread, being raised slightly against the force of the plunger 34 before causing any rotation of the tension wheel.

Except during the needle looping and retracting operations and the stitch setting action, with the use of inextensible cotton or linen thread, the auxiliary take-up is arranged to maintain an intermediate position between a pair of motion-limiting stops, comprising a set screw 74 threaded into the machine frame and a block 16 screwed to the machine frame, which block may be engaged by a set screw 78 passing through the auxiliary take-up. With proper adjustments of the auxiliary take-up for relatively inextensible thread, the reduced frictional force on the tension wheel usually is sufficient after setting each stitch to prevent slippage or other movement of thread in the substance of the work during formation of the succeeding stitch, into the set stitch, as will effect a substantial release of tension in that stitch. However, in some instances, the thread may slip through the substance of the work sufficiently to cause excessive looseness in spite of the high degree of tension applied to the thread by the increase of pressure on the tension wheel brake while setting each stitch. In the latter instance, the resulting seam will be faulty from looseness.

The mechanism for engaging and disengaging the abutment 52 from the brake supporting lever 46 is more fully described in the said Landroche patent. Briefly, this mechanism includes a pin 80 engaging the underside of the forward end of the actuating lever 56 and projecting laterally from a pivotally mounted block 82 having a recess within which a tooth-shaped projection 84 is mounted upon a lever 86 fulcrumed on a shaft 88 fixed in the machine frame and, at its forward end, the lever carries a roll 90 engaging a cam 92 on the sewing shaft 32.

As thus far described, the machine is substantially the same as in the patents above referred to. The elongation or extensibility of linen and cotton threads now in common use is illustrated in Fig. 9, in which the comparable characteristic stress-strain curves, correspondingly labeled, are indicated. Linen has an elongation before breakage of not substantially more than three per cent, whereas cotton may become elongated three times this amount before breakage. Cotton, however, is not as strong as linen and, consequently, the actual tension is less in the stitches formed of cotton thread since the adjustments required for cotton thread in the machine are such that a lower braking pressure is applied to the tension

wheel brake drum 42. In any event, the amount of linen or cotton thread taken up by the take-up is sufficient to cause the major portion of each thread length required per stitch to be pulled suddenly past the tension wheel against the relatively heavy tension directly after each stitch is set.

The rotation of the tension wheel with inextensible linen or cotton thread is indicated in Fig. 10 by the line designated "Linen." During the time the threaded needle is retracting from the work with a loop of thread to be employed in the formation of the succeeding stitch, a small further amount of thread may be pulled off the supply and drawn past the tension wheel if insufficient thread is provided by the auxiliary take-up. In some instances, this small further amount of thread is drawn past the tension wheel at some portion of the sewing cycle other than during the needle retracting stroke, depending upon adjustments.

An illustration of the relative proportions of tension wheel rotation while the machine is being operated with threads of different materials is given in Figs. 3 and 7 which show the relative amounts of thread drawn past the tension wheel while the needle is being retracted and while the take-up is setting that stitch. In Fig. 7, the amount of linen or cotton thread drawn past the tension wheel is assumed to be an inch and a quarter length for each stitch, which corresponds to the total amount of tension wheel rotation between the lines 94 and 96, the scale of the drawings being one third actual size. During that portion of tension wheel rotation between the lines 94 and 98, the frictional braking pressure applied to the tension wheel is increased, for instance, to an amount requiring a steady pull of fifteen pounds on the thread during the take-up stroke of the take-up. Thus, the major portion of the total thread is drawn past the tension wheel during the take-up action in substantially less than a sixth of the complete rotation of the sewing shaft, as explained above. The major portion of linen or cotton thread for each stitch, accordingly, may be drawn past the tension wheel in less than 25° of the sewing shaft rotation, necessitating sudden, jerky and irregular rotation of the wheel with consequent non-uniform lengths of thread being measured for successive stitches. During the remaining 335° of sewing shaft rotation, including the time of the needle retracting stroke, a small portion of the thread required in a succeeding stitch is drawn past the tension wheel under a decreased frictional braking pressure, as indicated by the angular distance between the lines 98 and 96.

A feature of the present invention includes substituting, in place of linen or cotton thread, the specially treated synthetic, fiber-forming plastic thread of the type hereinbefore referred to, to avoid the necessity of drawing past the tension wheel the major portion of total thread required in forming a stitch during a small part of the take-up stroke. As above explained in connection with Fig. 7 in the drawings, the amount of thread drawn past the tension wheel during the take-up stroke of the machine, according to the present sewing method, is limited to a very short length while the remainder of thread required in forming a stitch is drawn past the tension wheel gradually throughout the rest of each sewing cycle after the take-up stroke has been completed or through approximately 335° of the complete sewing shaft rotation without releasing the tension

on the previously formed stitch. In this way, jerky, irregular rotation of the tension wheel with overthrow is avoided and uniform lengths of thread for successive stitches of a seam are obtained.

The elongation characteristic of specially treated thread is indicated in Fig. 9 by the curve labeled "Nylon." For a comparable size, the specially treated thread has greater strength and is capable of greater elongation before its elastic limit is reached than either linen or cotton thread. Furthermore, even beyond the elastic limit, to a considerable extent, elongation of the specially treated thread is reversible, particularly after a lapse of time. With the improved machine, advantage is taken of this and other characteristics of the specially treated thread and full benefit is obtained from its contractility after the setting tension on each stitch is released. While thread composed of the other fiber-forming materials above mentioned is slightly weaker than that composed of nylon, corresponding changes may be made in the machine in proportion to the strength of thread utilized to produce the advantageous results of the invention. Thus, with rayon and vinylidene or Vynylon fiber thread, a slight reduction in auxiliary take-up spring pressure and in tension wheel brake pressure, from the pressures employed with nylon, within the range of adjustments obtainable in the machine, produces effective results.

The action of the tension wheel 26 in the illustrated machine, when such specially treated thread is used is illustrated in Fig. 3 of the drawings, in which the angular distance between the lines 100 and 102 represents the amount of rotation of the tension wheel required to supply thread for each stitch. The tension wheel is located a substantial distance from the point of sewing operations, the length of thread extending between the tension wheel and the sewing point being approximately eighteen inches. With this length of thread, an elongation occurs when a stitch setting tension is applied equal to several times the amount of thread used in each stitch.

Thus, if the take-up acts to take up an amount of thread substantially equal to that used in a stitch, insufficient tension will be applied to set the stitch during the first sewing cycle of a seam. A full stitch setting tension will not be set up in the thread until the third or fourth sewing cycle is completed, the thread between the tension wheel and the work being stretched during this time to supply the required thread without rotating the tension wheel. It is therefore apparent that the major portion of the tension in the thread is maintained throughout the formation and after setting of each stitch, so that retrograde slippage of the thread during formation of each stitch is prevented.

After a full stitch setting tension has finally been set up after the beginning of a seam, the take-up gives up thread only in an amount equal to that taken up in setting the stitch. In giving up thread, the thread itself contracts so that no substantial release of tension occurs, a limited amount of residual contractility remaining in the thread, depending upon its preliminary elongation. On account of the continuous elongation in the thread thus held over from one stitch to another, less thread actually is used in sewing than with relatively inextensible linen or cotton threads. Accordingly, the angular distance between the lines 100 and 102 is indicated as being somewhat less than the corresponding dis-

tance between the lines 94 and 96 in Fig. 7, representing rotation of the tension wheel with inextensible thread.

Since, by reason of the ability of the thread to stretch, it is elongated during the take-up stroke of the take-up, only a small amount of thread is drawn past the tension wheel at this time sufficient in length to maintain a uniform stitch setting tension in the thread, as indicated throughout the short angular distance 100, 104. This takes place at the time both abutments 50 and 52 engage the brake supporting lever 46 and a heavy frictional pressure is applied to the tension wheel brake. Because of the comparatively short length of thread drawn past the tension wheel at this time, a less jerky, more nearly uniform, movement takes place in the tension wheel from one cycle to another, with no opportunity for overthrow. After the stroke of the take-up has been completed, the braking pressure on the tension wheel brake is decreased by disengaging the abutment 52 from the brake lever 46. As soon as the braking pressure is relieved in this way, the elasticity in the thread causes the tension wheel to start rotating until the total amount of thread used in a stitch is drawn past the wheel. If the shorter portion of thread is drawn past the tension wheel between the lines 100 and 104 within 25° rotation of the sewing shaft 32, the remaining major portion of the thread is drawn past the tension wheel during 335° rotation of the sewing shaft, which obviously enables the tension wheel to rotate relatively slowly for the major portion of each sewing cycle. Also, the amount of thread drawn past the tension wheel while the heavy braking pressure is applied, being much less than that drawn past with a light pressure, a comparatively smooth uninterrupted rotation is produced in the tension wheel. The rotation of the tension wheel throughout a complete sewing cycle with the improved thread and corresponding changes in the machine is illustrated by the line designated "Nylon" in Fig. 8. The smoothness of this line in comparison with the "Linen" line is obvious.

To limit the tension on the thread during each stitch setting operation when highly extensible or elastic thread of the improved type is employed, the auxiliary take-up 24 is yieldingly actuated downwardly against the thread with a pressure of such stitch setting intensity that the auxiliary take-up is held from movement against the lower stop block 76 while relieved frictional pressure is applied to the tension wheel brake during stitch formation. Thus, instead of employing a spring 38 designed to actuate the auxiliary take-up against the force of the thread during the needle looping and restricting operations only, as when inextensible thread is employed, the spring is replaced with one having approximately four times the strength to hold the auxiliary take-up set screw 78 against the stop block 76 substantially throughout the sewing cycle except while a stitch is set, the elasticity of the sewing thread taking up and giving out thread as required during the formation of a stitch, without causing excessively rapid or jerky rotation on the tension wheel. Accordingly, the force of the spring 38 causes the auxiliary take-up to overcome the action of the tension wheel brake when the brake pressure is relieved. Furthermore, the major portion of the thread tension in setting each stitch is no longer caused by the inertia effect of the tension wheel and brake drum, as with the use of inextensible thread,

and accordingly a tension wheel brake spring of a greater strength is required to make up for the difference resulting from loss of inertia effect. Thus, the spring 68 employed with the improved thread has several times the strength of the spring employed with inextensible thread, inasmuch as the inertia of the tension wheel and brake drum affects the stitch setting tension in the thread in a comparatively small degree, the tension wheel rotation being smooth, without inertia effects.

With the adjustments thus made, the auxiliary take-up 24 acts as a stitch setting tension limiting device (see Fig. 3). Also, the action of the auxiliary take-up is such as to reduce still further the rotation required of the tension wheel during the stitch setting operation by giving up a short length only of thread during the stitch setting stroke of the take-up. It also prevents sudden, excessive strains in the nature of impacts on the thread under stitch setting tension and distributes the time of tension wheel rotation over a longer period so that a slower continuous rotation of the tension wheel results.

With the avoidance of sudden high-speed intervals of tension wheel rotation and a reduction in intensity of suddenly applied strains on the thread and correspondingly in the machine itself, a smoother sewing operation is produced with greater uniformity both in formation and in setting of successive stitches in a seam. Also, the moving parts of the machine and the bearing surfaces are less subject to damage from excessive impacts so that less attention is needed on the part of the operator in maintaining proper operation of the machine. A sewing machine operated in this manner, consequently, is able to operate over a longer period of time and with fewer adjustments than heretofore. Furthermore, the seam inserted actually is of a superior nature in that the threads continue to contract as the substance sewn yields and to draw the parts more tightly together for a substantial period of time after seam insertion. Thus, in the case of the inseam in a shoe, the difficulties formerly encountered are overcome in the manner hereinbefore set forth. In some instances where the upper of a shoe has been already tightened roughly about a last, it is possible by the use of the present method of operation to tighten the upper sufficiently by means of the contracting thread to eliminate the necessity of a separate lasting operation.

The improved action of the thread to produce a tight seam of superior nature in sewing sole

leather is an evidence that the invention is present or being practiced, particularly when a seam first inserted shows incomplete tightening of the parts sewed, one against the other, and when, after a lapse of time, the parts are drawn much closer together. Also, an advantage of the present invention is apparent when the use of a liquid lubricant or hot wax on the thread is found unnecessary to effective insertion of a tight seam in sole leather, the ability of the thread to stretch and contract being far beyond the range of similar qualities in threads previously employed for such purposes.

The ability of the thread to contract in the manner outlined is due in part to treatment and elongation of the thread prior to its use. In certain instances, the contractility is enhanced after a seam has been inserted by the presence of moisture in the sole leather or the action of tannin or the presence of other common astrigent chemicals brought into contact with the thread.

The nature and scope of the invention having been indicated and a particular manner of carrying out the invention having been described, what is claimed is:

That improvement in methods of making shoes which comprises assembling a sole member and an upper upon a last, providing an elastic thread of fiber-forming material treated to insure substantial residual contractility after a stitch setting tension is applied, inserting a seam of said thread connecting the sole member and upper with stitches having insufficient tension in the thread during the formation of the stitches to bring the parts firmly together but having sufficient residual contractility to draw the parts together after the seam is inserted, and retaining the shoe on the last until the thread in the stitches contracts sufficiently to bring the upper into accurate conformity with the shape of the last before removing the last from the shoe.

JAMES P. FREDERICKSEN.
